UNITED STATES PATENT OFFICE

HARRY DUDLEY STEVENS, OF STOKE, COVENTRY, ENGLAND

WALKING STICK SEAT

Application filed February 26, 1930, Serial No. 431,532, and in Great Britain September 18, 1929.

This invention relates to walking-stick seats and has for its object to provide a new or improved construction therefor which will enable them to be produced and sold at a price much below the comparatively exclusive prices which at present prevail. Apart from the question of price, however, the improved seat also embodies useful features which are not to be found in such seats as at present marketed.

The improved seat is constructed wholly or mainly of metal and in such a manner as to avoid the necessity for the employment of skilled labour or for elaborate machining and finishing operations.

As compared with existing seats of the same type the improved seat whilst being more than sufficiently strong for its purpose is much lighter to carry and perfectly rigid when used as a walking-stick.

Where the stick is made adjustable the invention includes a new or improved method of locking and releasing the telescoping members of the support.

The invention also includes a new or improved method of attaching and releasing the ground plate or disc which when the stick is in use is introduced onto the lower end to prevent the stick sinking into soft ground and which when the stick is not in use is carried by a boss on the seat bracket.

In the accompanying drawing,

Figure 1 represents an adjustable walking stick seat embodying the present invention.

Figure 2 is a plan of the same with the seat portions extended.

Figure 3 is a sectional view on a larger scale of the lower end of the adjustable support.

Figures 4 and 5 are sectional views at right angles to each other of the seat bracket, Figure 4 showing the boss and ground plate and Figure 5 the seat elements turned upwards to form a handle.

Figures 6 and 7 are plan and sectional views respectively of the ground plate and its locking means.

Figure 8 shows the application of the invention to a non-adjustable walking stick seat.

Like parts are designated by similar reference characters throughout the drawing.

Referring to the drawing, the support *a* consists of a metal tube of a gauge adequate to sustain the weight of the user. The said tube may be finished exteriorly either by plating, enamelling or by a covering of leather or other suitable material. The support can either be made of a fixed length, as shown in Figure 8, or be capable of extension in which latter case it can, as shown in Figures 1 and 3, be of telescopic construction. In either case it is shod at the bottom end with a ferrule *a*¹.

The seat proper at the upper end of the support comprises a pair of wire loops *b*, *b* made of steel suitably heat treated to impart a certain degree of resilience to the seat. The said loops, which may be of any appropriate shape, are pivoted in a bracket *c* secured to the upper end of the support *a*. When extended or turned down to form the seat each loop overhangs and takes a bearing upon the adjacent edge of the bracket *c* in close proximity to its pivot. The degree of resilience obtained in any given case will therefore depend upon the gauge and temper of the wire and the distance between the edge of the bracket and the point along the overhanging part of the loop where the weight of the user principally falls. The comfort of the user is further assured by providing the wire of the loops, with a covering *b*¹ of some resilient material such as leather with or without an intermediate covering *b*² of india-rubber, or padding.

The bracket *c* may consist of a stainless steel or other metal casting, or it may, alternatively, be formed of sheet metal by a pressing or stamping operation. The said bracket is of box formation open at the top and provided on its under side with a socket *c*¹ within which the upper end of the tubular support *a* is rigidly fixed in any suitable manner, as by brazing or by screwing or other form of mechanical connection. The bracket is provided with a pair of horizontal pins or rivets *c*² which are fixed in the opposite walls thereof and constitute the pivots for the wire loops or seat members *b*, *b*. A tubular distance

piece c^3 is preferably introduced onto each of these pivot pins between the eyes b^3 of each loop, or alternatively the distance pieces may be cast solid with the bracket.

In order that the seat members when used as a handle shall be rigid with the support the bracket c is provided with a stop which may conveniently take the form of a dividing wall c^4 formed integrally with the bracket and extending across the same between the pivot pins so as to limit the folding movement of the seat members in such a manner that when they are gripped together in the position shown in Figure 5, they form a handle which is quite rigid with the support.

Where the improved stick is made adjustable in height, Figures 1 and 3, the lower end is provided with a tubular member a^2 adapted to telescope within the support a and to be locked in its adjusted position therein. For this purpose the locking means is preferably concealed within the interior of the telescoping members and, in the form shown, consists of a pin or detent d which is mounted in a hole e in the inner telescopic tubular member of the stick from which it normally protrudes laterally under the influence of a spring f concealed within the said member. The said pin is adapted to engage with any one of a longitudinal series of holes g formed for the purpose in the outer telescopic member of the stick so as to prevent relative movement between the two telescoping members. In order to release the latter prior to adjustment, all that is necessary is to depress the outer protruding end of the pin d against the action of the spring into its hole in the outer member when the stick can be extended or shortened as desired, the pin automatically snapping into engagement with another of the holes g in the outer member and effectually locking the parts in the new position. The protruding end of the pin is suitably chamfered or rounded so that it is not necessary to use a tool to force it right back before the stick can be adjusted.

The pin may be spring mounted in any suitable manner, as by means of a blade spring f which, as shown in Figure 3, is loosely inserted in the open inner end of the inner telescopic member a^2 and formed so as normally to maintain the pin d in its operative position. Advantage may be taken of utilizing the same spring f to prevent any tendency to rattle or free play between the telescopic members of the stick. For this purpose one end f^1 of the spring may extend beyond the open inner end of the inner telescopic member and be so shaped as to press firmly against the inside wall of the outer telescopic member a in a direction opposite to the pressure exerted by the part carrying the pin. This effect is obtained by bending the ends of the spring substantially in the manner shown.

The improved locking device is equally ap-

plicable where adjustment is made at the upper end of the stick, in which case the bracket c would be carried by the inner telescopic member a^2 .

The plate or disc h , which is normally carried by a boss c^5 on the bracket c and when the stick is in use is transferred to the ferrule a^1 to prevent the latter sinking into soft ground, is removably secured in either of these two positions by means of a locking device which when the disc is introduced onto the said boss or the ferrule automatically locks the same in position thereon. In its preferred form the said locking device consists of a blade spring i which loosely encircles a boss h^1 on the plate and is secured thereto at its ends by a screw h . At a point diametrically opposite the screw the spring is provided with an inwardly directed pin or peg l which is adapted to enter a hole m in the said boss on the plate and to protrude therethrough into engagement with an annular groove n in the ferrule a^1 or lower end of the stick, Figure 3, or in the boss c^5 on the bracket, Figure 4. The action of the locking device is such that, normally the blade spring i holds the pin l in its operative position so that when the plate is introduced into either of its two positions the pin is first pushed outwardly against the pressure of the spring until it comes opposite the annular groove n when it automatically snaps home under the influence of the spring and securely locks the plate in position. In order to remove the plate the spring i is compressed between the fingers along a diameter substantially at right angles to that containing the pin l and screw h when it will be found that the resulting distortion of the spring will cause the said pin to move out of its operative position. Alternatively, the locking pin may be carried by a bow-shaped spring embracing a portion only of the boss on the plate and having its ends returned on themselves for a short distance and retained in position between stops on the plate and the boss of the latter. The pin is carried by the middle of the spring and operates in the same way as above described, being released by pinching the ends of the spring against the boss of the plate which causes the middle part of the spring to move away from the boss and so withdraw the peg from engagement with the annular groove.

The bottom end of the stick or the ferrule a^1 may be screw-threaded internally or otherwise formed to receive an india-rubber pad o or a spike.

I claim:

1. In a seat stick having a cane portion, a bracket mounted on the upper end of said cane portion, a pair of anchoring pins mounted in said bracket and extending parallel to each other, and a division plate rigid with said bracket and extending from end to end

thereof parallel to, between, and equi-distant from, said anchoring pins respectively, the said bracket having sides respectively extending parallel to and adjacent the respective pins, in combination with a pair of resilient loop members respectively mounted on said pins to swing about the respective axes thereof, each said loop member being adapted to swing in an arc not exceeding ninety degrees defined at one end by the division plate and at the other end by the edge of the respective cooperating side portion of the bracket.

2. In a seat stick having a cane portion, a bracket mounted on the upper end of said cane portion, a pair of anchoring pins mounted in said bracket and extending parallel to each other and a division plate extending from end to end of said bracket parallel to, between, and equi-distant from, said anchoring pins respectively, the sides of said bracket extending upwardly beyond a horizontal plane intersecting the axis of said pins in combination with a pair of resilient loop members respectively connected to said pins to respectively swing about the same, each said loop member being adapted to swing outward away from each other and to be engaged between its free end and its point of connection to its respective pin, before it has swung down horizontally, by the edge of the adjacent side of said bracket.

3. In a seat stick having a cane portion, a bracket mounted on the upper end of said cane portion, a boss extending from said bracket, said boss being formed with an annular groove, and the lower end of said cane portion being formed with an annular groove, said annular grooves being of the same size, in combination with a ground plate adapted to slip on either the lower end of said cane portion or on said boss, a pin extending through the wall of said ground plate and adapted to extend into either of said grooves, and a leaf spring of slightly elliptical formation mounted concentrically on the said ground plate and secured at one end of its minor axis thereto, and carrying said pin at the other end of said minor axis, whereby compression of said spring in the direction of its major axis will serve to withdraw the pin from its operative position.

4. In a seat stick having a telescopic cane portion, the external telescopic member being formed with a longitudinal series of perforations, and a lock pin extending through the inner telescopic member and being adapted to fit into any one of said perforations to lock said members in any desired adjusted position, in combination with a leaf spring extending for the most part within said inner telescopic member and having an end portion extending into and bearing against the outer telescopic member, said spring carrying said lock pin and being entirely disposed

within the interiors of said members and having its end portions bent inward toward each other so as to result in putting the end portions of the spring under compression and having the extreme end portions of the respective ends of the spring in engagement with the respective telescopic members to eliminate play between said members.

In testimony whereof, I have signed my name to this specification at Coventry, England, this fifteenth day of February, 1930.

HARRY DUDLEY STEVENS.
